LIFE JACKET

Willard E. Crotty, Quincy, Mich., assignor to Crotty Corporation

Application May 11, 1955, Serial No. 35,943

Term of patent 14 years

Figure 2 is a back perspective view thereof, with the one shoulder strap broken away to avoid overlap and conflict between the views of the drawing.

I claim:

The ornamental design for a life jacket, as shown and described.
